(57) **CLAIM**

The ornamental design for a horizontal electronic stimulus
delivery apparatus, as shown and described.

DESCRIPTION

FIG. 1 is a perspective view of a horizontal electronic stimulus
delivery apparatus of the present invention;

FIG. 2 is a front elevational view thereof;

FIG. 3 is a rear elevational view thereof;

FIG. 4 is a top plan view, the bottom plan view being a
mirror image thereof; and,

FIG. 5 is a right side elevational view, the left side eleva-
tional view being a mirror image thereof.

Portions of the horizontal electronic stimulus delivery appa-
ratus shown in broken lines are for illustrative purposes only
and form no part of the claimed design.
